Filed Jan. 16, 1959, Ser. No. 787,266

6 Claims. (Cl. 13—10)

The present invention relates to a method and apparatus for forming ingots. This method and apparatus were devised particularly for use in connection with titanium and other similar meltable materials which have high melting points and a chemical affinity for an atmospheric gas, such as oxygen, when heated to the neighborhood of their melting point. However, the method and apparatus described are not necessarily limited to use with such materials, but may be used to advantage with other materials, e.g., steel, whenever an ingot of high purity is desired.

The prior art methods of making titanium have been adapted to use as raw materials either titanium sponge, as in the apparatus disclosed in U.S. Patent No. 2,800,519, issued to Robert J. Garmy on July 23, 1957, or to use consumable electrodes formed of compressed sponge, as in the apparatus described in the copending application of Robert J. Garmy, Serial No. 698,256, filed November 22, 1957, now Patent No. 2,973,452. The adaptability of such apparatus to the use of scrap titanium is limited. In fact, so far as is known, there has been no practical process, prior to the present one, which was adaptable to the use, as a raw material constituting the entire initial charge, of scrap titanium in all of the many forms in which scrap is produced industrially. This lack of ability to utilize scrap has kept the prices of titanium and other such materials at high levels, and has limited their adaptation to many commercial uses.

An object of the present invention is to provide a method and apparatus for forming ingots of titanium and the like which is capable of using as a raw material titanium scrap in practically any form.

Another object is to provide an improved method of melting scrap metal, which method is adaptable for use with difficultly meltalble metals such as titanium, zirconium and the like.

Another limitation of the prior art methods and apparatus for producing ingots of titanium and the like has been that only a small amount of material being melted was maintained molten at any given time. Typically, the ingot was built up in a vertically extending generally cylindrical crucible, raw material being added at the top of the crucible throughout the ingot forming process. The rate of addition of raw material and the rate of heat supply were controlled so that only a small portion of the material in the crucible was liquid at any time. As the ingot built up in the crucible, it consisted of a solid ingot with a pool of molten material on its top, to which material being melted was continually added, and from which material was continually solidifying at the bottom of the pool.

With such methods and apparatus, it is difficult to form an ingot of large dimensions having homogeneous composition throughout its body. In order to form an ingot of the best possible quality, a substantial volume of molten metal must be maintained molten and mixed just prior to pouring. The prior art methods and apparatus were not capable of maintaining sufficient quantities molten and thoroughly mixing them to ensure the best homogeneity of the ingot.

Another object of the present invention is to provide a method and apparatus for forming ingots of materials of the type described, in which the material for the en-

tire ingot body is maintained molten and is poured in a molten state into a mold.

Another object is to provide a method and apparatus of the type described, which is capable of holding in a molten state a quantity of metal sufficient to cast a sizable object in a shape or form other than a cylindrical ingot.

A further limitation of the prior art methods and apparatus for forming ingots from titanium and the like is that the superheat of the titanium was limited and also was not closely controllable. By superheat is meant the difference between the melting point of titanium and the higher temperature at which it is maintained in the furnace.

15 The previous furnaces were limited in the metallurgical results they could produce in their ingots by reason of their inability to reach high superheat temperatures and to control those temperatures accurately.

20 A further object of the invention is to provide an improved method and apparatus for forming ingots of titanium and the like, in which a meltalble material may be maintained, in substantial volume, at temperatures considerably above its melting point, just prior to pouring.

25 It has been proposed to construct furnaces for the melting of titanium and the like, which have been termed "skull" furnaces from the fact that the crucible in which the material was melted utilized as a liner, a thick, hollow, hemispherical layer of material being melted. Such a layer is referred to as a "skull." Commonly, the skulls in the prior art furnaces have been rather thin (about 1" thick), and no attempt has been made to control the skull thickness during the melting operation. In the previous methods and apparatus using skulls, the crucible has been formed of refractory material or the like, having low thermal conductivity.

30 Another object of the present invention is to provide a skull furnace in which the thickness of the skull may be controlled during the melting operation. A further object is to provide a skull furnace of the type described in which the skull thickness is controlled by using a cooled copper shell for the crucible, and balancing the heat input through the arc against the heat extracted through the shell.

35 The foregoing and other objects of the invention are attained in the method and apparatus described herein. Typically, the apparatus comprises a crucible located inside a sealed enclosure. Means is provided for evacuating the enclosure. The crucible is tiltable so that material melted in it may be poured from it into one or more molds which are also located inside the enclosure. For the purpose of charging the crucible, the enclosure may be opened and the crucible loaded with titanium in a convenient form, either sponge or scrap. The enclosure is then closed and evacuated and an arc is struck between a consumable electrode and the material in the crucible. The consumable electrode continues to add material to the crucible as long as its arc is maintained, and is effective to melt down the material in the crucible.

40 The crucible comprises an outer shell of copper or other material having high thermal conductivity, and a skull of the material being melted, which skull is built up and maintained at the inner surface of the shell, by the use of cooling means on the outside of the shell. The skull must have an appreciable thickness and be strong enough to contain the melt. The melting with the consumable electrode continues until all the material originally supplied and that added by the consumable electrode has been melted into a large unitary mass which fills the crucible to a desired level. The arc from the consumable electrode is then extinguished and it is withdrawn. In its place a plurality of non-consumable electrodes are moved into arcing relationship with the surface

of the liquid mass. The power supplied to these electrodes is controlled to determine the temperatures developed in the mass of the material. The heat loss from the outside of the mass of material through the solid skull and the shell is controlled by controlling the temperature of the coolant (a certain amount of heat is also lost by radiation from the liquid surface), and the heat supplied to the mass is determined by the power supplied through the non-consumable electrodes. The equilibrium temperature and thus the degree of superheat maintained in the mass, and the thickness of the skull, may be readily controlled by so controlling the heat supply and heat loss.

In order to prevent contamination of the ingot and to refine the melt by the extraction of hydrogen, it is highly desirable to maintain a high vacuum in the furnace. From the standpoint of purity, the vacuum should be somewhat higher than that which produces the best arc characteristics. In order to enable the use of such high vacuum without adversely affecting arc characteristics, the non-consumable electrodes are made hollow and a continuous supply of an inert gas, e.g., a mixture of argon and helium, is supplied through the hollow electrodes so that the pressure conditions in the immediate neighborhood of the arc are raised somewhat above the highly evacuated conditions elsewhere in the furnace.

In order that the molten material in the crucible may be thoroughly mixed, there is provided a coil encircling the outside of the crucible, which is supplied with direct electric current sufficient to establish a vertically extending magnetic field throughout the crucible. This field reacts with the currents flowing through the molten material in the crucible so as to stir that material continuously in one direction, thereby keeping it well mixed while preventing the formation of eddies or the like which might result in the formation of stationary portions of the material.

After the material has been brought to a desired degree of superheat and maintained there for a desired length of time, the material in the crucible is poured into a mold or molds located within the enclosure. The pouring is accomplished by withdrawing the non-consumable electrodes and tilting the crucible so that the material therein pours over a suitably formed pouring spout or lip into the mold. The fulcrum about which the crucible tilts is preferably located near the spout so that the path of the pouring stream remains nearly the same throughout the pour.

Other objects and advantages of the invention will become apparent from a consideration of the following specification and claims, taken together with the accompanying drawings.

In the drawings:

FIG. 1 is a vertical sectional view of an ingot forming furnace embodying the invention, taken on the line I—I of FIG. 3;

FIG. 2 is a cross-sectional view taken on the line II—II of FIGS. 1 and 3, showing the main enclosure of the furnace in FIG. 1 and certain auxiliary apparatus located below the main furnace and not included in FIG. 1;

FIG. 3 is a horizontal sectional view of the furnace of FIG. 1, taken on the line III—III of FIGS. 1 and 2;

FIG. 4 is a vertical sectional view of one of the non-consumable electrodes in the furnace of FIGS. 1 to 3;

FIGS. 5 to 11 show diagrammatically, successive steps in the process of forming an ingot using the furnace of FIGS. 1 to 4;

FIG. 12 is an overall front elevational view of a modified form of furnace embodying the invention, with certain parts omitted for clarity;

FIG. 13 is an overall side elevational view of the furnace of FIG. 12, with certain parts omitted for clarity;

FIG. 14 is an enlarged elevational view of the enclosure of the furnace of FIG. 12 with certain parts broken

away and others shown in section to illustrate the internal parts;

FIG. 15 is a view similar to FIG. 13, somewhat enlarged and showing only the main enclosure of the furnace and with certain parts broken away and others shown in section;

FIG. 16 is a sectional view taken along the line XVI—XVI of FIGS. 12 and 13;

FIG. 17 is a view of the crucible and its supporting structures taken from the rear as they appear in FIG. 14, and substantially enlarged;

FIG. 18 is a plan view of the crucible of FIG. 17;

FIG. 19 is a left side elevational view of the crucible of FIG. 17;

FIG. 20 is a right side elevational view of the crucible of FIG. 17;

FIG. 21 is a fragmentary view similar to a portion of FIG. 14, but somewhat enlarged;

FIG. 22 is a plan view of FIG. 21, showing the top of the furnace with certain parts removed;

FIG. 23 is a vertical cross-sectional view of a modified form of non-consumable electrode which may be used in the furnace of FIGS. 14—22;

FIG. 24 is a horizontal cross-sectional view, taken on the line XXIV—XXIV of FIG. 23;

FIG. 25 is a diagrammatic illustration of a coolant circulation system in the furnace of FIGS. 14—22; and

FIG. 26 is a diagrammatic illustration of electric circuits used in connection with the furnace of FIGS. 14—22.

The furnaces as disclosed herein are loaded by first placing a quantity of scrap or sponge in the crucible while the crucible is open to the atmosphere. The furnaces are then closed and evacuated. An arc is then struck between a consumable electrode and the material in the crucible. This arc is effective to melt down that material and to add further material. After the original charge is all melted, the consumable electrode is withdrawn and the temperature of the melt is further raised by the use of non-consumable electrodes.

FIGS. 1 to 4

There is shown in FIGS. 1 to 3, a furnace comprising an enclosure or crank 1 of generally circular horizontal cross-section. The enclosure 1 is provided with an outlet connection 2, which is connected to a vacuum pump, not shown, by means of which the pressure inside the enclosure 1 may be reduced to and maintained at a sub-atmospheric pressure. The enclosure 1 is provided with a cover plate 3. Projecting upwardly from the center of the cover plate 3 is an electrode tube 4 for receiving a consumable electrode 5 of the material to be melted. The upper end of the electrode 5 is gripped by a holder shown diagrammatically at 6 and attached to the lower end of a lead screw 7 driven by a rotating nut 8 which is operatively connected, as shown diagrammatically in the drawing, to a motor 9.

The lead screw 7 is hollow, and water or other suitable liquid coolant is circulated through it by means of hose connections 10 and a coupling 11. Electricity is conveyed to the electrode 5 by means of brushes 12 which engage the ends of the rotating nut 8 and which are connected through suitable connectors to terminals 13 located on the outside of the electrode tube 4.

The lower end of the electrode 5 projects downwardly into a crucible 14, comprising a cylindrical shell 14a, whose structural details may be similar to that shown in the copending application of Robert J. Garmy, Serial No. 651,328, filed April 8, 1957, now Patent No. 2,950,094, and a skull 54 within the shell. The crucible 14 has cooling jackets 15 and 16 on its bottom and sides, respectively, through which water or other suitable coolant may flow. The crucible 14 also has a coil 17 for arc stabilizing and stirring purposes as shown, and claimed in the copending application of Robert J. Garmy, Serial

No. 671,154, filed July 11, 1957, now abandoned. One side of the crucible 14 is provided on its upper end with a pouring spout 18 which may be constructed of graphite.

The crucible 14 rests on a framework 19 supported on a plate 20 of somewhat larger diameter than the framework 19 and adapted to engage at its edge a flange 1a which surrounds an opening in the bottom of the enclosure 1. The plate 20 rests, as best seen in FIG. 2, on a platform 21. This platform 21 may be raised or lowered by means of lead screws 22 mounted vertically in suitable bearing structures in a framework 23 carried by a truck 24 provided with axles 25 and wheels 26 for movement along rails 27. A suitable motor (not shown) is provided for driving the lead screws 22 concurrently.

Inside the furnace enclosure 1 and above the crucible 14 there are provided three non-consumable electrodes 28, the details of which are shown in FIG. 4. Referring to that figure, it may be seen that each electrode 28 comprises a tip 29, an internally threaded coupling member 30 and a power supply tube 31. The tip 29, which may be either of graphite or tungsten, is hollow to provide a central passage 29a. The upper end of the tip 29 is externally threaded to fit internal threads on one end of the coupling 30. The coupling 30 has a central aperture 30a aligned with the passage 29a and in fluid communication with it. A gas supply pipe 32 projects into the coupling 30 and has its lower end extending into the aperture 30a. Pipe 32 is concentric with the power tube 31. Another cylindrical tube 33 is concentric with the tube 31 and the gas supply tube 32 and lies between those two tubes. The tube 33 has its lower end terminating short of the bottom of the upper threaded recess in the coupling 30, so that coolant liquid may flow downwardly through the tube 33 and upwardly between the space between tube 33 and power tube 31. The lower end of tube 31 is externally threaded to engage the internal threads on the coupling 30.

The upper end of the tube 31 is provided with coolant supply and drain couplings and with suitable current supply couplings. These couplings are not shown in drawings, and may be generally similar to those shown in Garmy Patent No. 2,800,519, mentioned above.

An auxiliary non-consumable electrode 34 is provided, generally similar in structure to the electrodes 28. The electrode 34 includes a power tube 35, which extends upwardly through the cover 3 and has its upper end attached to a carriage 36 supported by means of traveling nuts on a lead screw 37 driven by a motor 38. The electrodes 28 and power tubes 31 are driven by similar motors and supporting mechanisms, which have been omitted from the drawing for the sake of clarity.

Within the enclosure 1 and aligned with the pouring spout 18, there is provided a turntable 39 which supports a plurality of molds 40 and 41. The mold 40 is generally similar in structure to the crucible 14, having water cooled sides and base to provide for rapid chilling of the molten material poured into it. The molds 41 are of more conventional structure, being formed of graphite or the like. Each mold may have a target plate 42, 43 in its bottom formed of the same material which is to be poured into it. The enclosure 1 is provided with access doors 44 on either side, by means of which access may be gained for removal of the molds 40 and 41 and the ingots poured therein. The upper side of the enclosure 1 is provided with a tube 45 closed at its outer end by a glass 46, through which the operation of the mechanism inside the enclosure may be observed. The entire enclosure 1 is mounted in a thick walled chamber, one of whose walls is shown at 47 in FIG. 1. A heavy observation window 48 is provided in the wall 47. Suitable control mechanism for the furnace is located outside the window 48.

A hopper 49 (FIG. 2) is mounted within the enclosure 1 on a pair of links 50, which permit it to be moved from the position shown in full lines in FIG. 2 to the

dotted line position, where its inner end extends over the crucible 14. The hopper 49 may be fed with supplementary scrap or sponge material through a conduit 51 which extends through the upper side of the enclosure 1. Suitable external means may be provided for feeding sponge into the conduit 51, such as that shown, for example, in Patent No. 2,800,519, mentioned above.

FIGS. 5 to 11

These figures illustrate diagrammatically the improved method for forming ingots using the apparatus of FIGS. 1 to 4. The apparatus shown in these figures consists of a crucible 14 having a side wall water jacket 16 and a base water jacket 15.

The first melting run with a given crucible shell is utilized to form a skull which is used on later melting runs of material having the same composition.

For the first melt, there is placed in the bottom of the crucible shell a preformed slab 52 of titanium or other metal to be melted, as shown in FIG. 5. Upon the slab 52 there is loaded a supply of material to be melted, as shown at 53 in FIG. 6. This load may consist entirely of scrap, or it may be scrap mixed with titanium sponge. After the crucible is so loaded and the furnace evacuated, the consumable electrode 5 is lowered to the position shown within arcing distance of the scrap 53 and an arc is started, thereby melting the scrap, and also melting the electrode 5 gradually. The molten material from the arc flows down over and melts the unmelted material. Smaller arcs are developed at this time throughout the pile of scrap and sponge which are also effective in melting the material. This phase of the process commonly proceeds with much turbulence, sputtering and splattering of the molten material. Throughout this phase, the molten material is stirred by the action of the coil 17.

The process just described is capable of melting down titanium scrap in whatever shape or condition it may be, so long as the pieces are small enough to be received in the crucible. Several factors are present which promote the melting action, including: (1) the small local arcs formed between the abutting pieces of scrap; (2) the major arc formed between the consumable electrode and the pile of scrap; and (3) the molten material flowing from the major arc down over the other pieces. While the melting may be successfully accomplished without the use of the stirring coil, it has been found that the stirring coil speeds the melting process considerably.

All of the material supplied to the crucible eventually is melted and most of it solidifies again as a solid body 54 of titanium, shown in FIG. 7 at 54, having a small molten pool of titanium 55 in its upper surface. After this condition is reached, the consumable electrode 5 is withdrawn, and the nonconsumable electrodes 28 are lowered so that their tips 29 are adjacent the surface of the pool. Arcs are struck at those electrodes and are supplied with electrical energy sufficient to melt a substantial portion of the titanium in the crucible, lowering the liquid-solid interface to the line indicated at 56 in FIG. 8 which, at the center, is close to the position of the upper surface 60 of the original slab 52 of FIG. 5. The temperature maintained in the pool 55 and the thickness of the solid titanium body 54 may be controlled by regulating the heat supplied by controlling the amount of power supplied through the electrode tips 29, and regulating the heat loss 65 by controlling the flow of coolant through the cooling jackets 15 and 16. After a desired volume of titanium has been brought to the liquid condition in the pool 55 and raised to a suitable degree of superheat, the three electrodes 29 are withdrawn, and the auxiliary electrode 34 is lowered adjacent the pouring spout of the crucible to melt away the solid material which may be clogging that spout, as shown in FIG. 9. If desired, the auxiliary electrode 34 may be brought into action before the electrodes 29 are withdrawn. During all the foregoing operation, current is maintained flowing in the stirring coil

17 to keep the pool agitated so that the composition of the pool is homogeneous. After the material near the pouring spout has been melted, the crucible is tilted by suitable mechanism included in the supporting frame 19, and not shown in the drawing, so that the pool 55 is poured into the mold 40, as shown in FIG. 10. After the pouring is completed, the material in the crucible 14 has the structure shown in FIG. 11. The titanium body 54 in the crucible roughly conforms to the internal contour of the crucible, and is known as a "skull." It is allowed to remain in that contour and subsequent loads of material are deposited within the skull 54, rather than on a slab such as shown at 52 in FIG. 5.

FIGS. 12 to 26

There is shown in these figures a modified form of furnace embodying the apparatus of the present invention, and with which the process of the invention may be practiced. This furnace is generally indicated by the reference numeral 60, and comprises a large generally cylindrical enclosure or tank 61 having a crucible access opening 62 at the left hand side as viewed in FIG. 12, and a mold access opening 63 at the rear, as viewed in the same figure. Both openings are closed by suitable covers 62a and 63a. The enclosure 61 rests on legs 64 and is preferably provided with cooling and strengthening fins, one of which is shown in FIG. 12 at 61a. The others have been omitted to simplify the drawing. On the top of the enclosure 61 there is provided a central cylindrical extension 65. Projecting upwardly from the top of the extension 65 is a central electrode tube 66, which encloses a consumable electrode 67, which may be generally the same as the electrode 5 of FIG. 1. The mechanism for supporting the electrode 67 within the tube 66 may be the same as that shown and claimed in the copending application of Robert J. Garmy, Serial No. 698,256, filed November 22, 1957, now Patent No. 2,973,452. This apparatus will be described only briefly herein. It comprises a platform 68 horizontally movable along rails 69 by means of a motor 70. A pair of masts 71 extend upwardly from the platform and are joined at their upper ends by a crossbar 72. A cross-head 73 is guided for vertical movement along the masts 71, and is moved vertically by a pair of concurrently driven lead screws 74. The lead screws 74 are driven by a motor 75 mounted on the platform 68. A power tube 76 is attached at its upper end to the cross-head 73. The power tube 76 extends through a suitable seal in a cover (not shown) for the upper end of the electrode tube 66, and supports the electrode 67 within the tube by means of a suitable clamp, which may be the clamp shown and described in the copending application Arthur F. Jones and Donald A. Rice, Serial No. 697,702, filed November 20, 1957, now Patent No. 2,964,580.

The platform 68 and the apparatus mounted thereon are shiftable from the positions shown in the drawing, which are their positions during furnace operation, to positions shifted somewhat to the left as viewed in FIG. 12, which positions are utilized during loading of a new consumable electrode into the furnace.

Also projecting upwardly from the top of the extension 65 are three circumferentially spaced electrode tubes 77, somewhat smaller in diameter than the central electrode tube 66. The tubes 77 enclose non-consumable electrodes 78 and are provided at their upper ends with seals so that the electrodes 78 may slide in and out. Each electrode 78 is driven by a lead screw 79, which is in turn driven by a motor 80 mounted on a fixed platform 81 (FIGS. 12 and 16) just below the furnace operating position of the movable platform 68. The lower end of each electrode 78 is provided with a tip 159 (FIG. 15). Columns 78a extend alongside the electrodes 78 and lead screws 79. These columns serve as supports for limit switches 79a which cooperate in controlling the lead screws 79. The electrode 78 and tip 159 are made hollow

5 for the purpose of feeding inert gas to the vicinity of the arc when the electrode is being used, in a manner similar to the electrodes 28 of FIGS. 1 to 4. The details of construction of electrodes 78 are described below in connection with FIGS. 23 and 24.

10 Inside the enclosure 61, as best seen in FIGS. 14 and 15, a crucible assembly 82 is mounted on a carriage frame 83 having wheels 84, 84a by which it is movable along rails 85 which are aligned with the crucible access port 62 and the cover 62a.

FIGS. 17 to 20

15 The crucible assembly 82 includes a generally cup-shaped crucible shell 86, preferably formed of copper or other material having high electrical conductivity and thermal conductivity. The crucible shell 86 is generally cup-shaped and has fastened to the outer edge of its periphery a rim 88, preferably of steel, shown as having a right angle cross-section. The horizontally projecting flange of the rim 88 is fastened by suitable means to the horizontal flange of an angle section ring 89, also preferably of steel, whose vertical flange is attached to a hoop 90, also preferably of steel, and having a channel-shaped cross-section. One side of the lower flange of the 20 hoop 90 rests on a beam 91 which is attached at its ends to trunnions 92 rotating in trunnion blocks 93 supported by means of plates 94 and 95 on the carriage frame 83. A portion of the crucible shell 86 and an aligned portion of the hoop 90 are cut away and a pouring spout 96 is inserted in these cut away portions. The pouring 25 spout 96 may be of graphite or other refractory material which is not attacked by the material being poured.

30 Projecting laterally from opposite sides of the ring 90 are a pair of pivot pins 97. Each pivot pin 97 is supported on one end of a telescoped cylinder 98a, 98b. The cylinders 98a and 98b serve as jacks for lifting the crucible assembly 82 and tilting it about the trunnions 92 so as to pour molten material from the crucible shell 86 through the spout 96 into a mold 99 (see FIG. 15), which may be positioned beneath that spout. The crucible assembly 82, which includes crucible shell 86, ring 90, and associated parts is supported entirely by the beam 35 91 and the jack cylinders 98a, 98b.

35 The axis about which the crucible assembly tilts (i.e., the axis of trunnions 92) is located close to the pouring spout 96, so that there is a minimum change in position of the pouring stream as the crucible assembly is tilted between its full and empty positions.

40 The cylinders 98b are provided with bevel gears 100 which cooperate with bevel gears 101 fixed on a shaft 102. The shaft 102 may be driven from outside the enclosure 61 by means of a motor 103 which drives a shaft 104 (see FIG. 14) which extends through a suitable seal in the enclosure 61 and through a slip friction clutch 105 to the shaft 102. Rotation of the bevel gears 100 turns the cylinders 98b and thereby operates suitable mechanism, e.g., cooperating threads on the cylinders 98a, 98b to control the expansion and contraction of those cylinders.

45 50 The electric current for the arcs within the crucible assembly 82 flows from the arcs through a metal skull 110 and the crucible shell 86 and thence through a block 106 welded on the bottom of shell 86 and connected through a bus bar 107 to switch fingers 108. The complete circuits for the arc currents are described below in connection with FIG. 26.

55 60 The outside surface of the crucible shell 86 has mounted thereon a cooling coil 109 formed of tubes or pipes, through which a liquid coolant, e.g., water, is circulated. The coolant is effective during operation of the furnace to freeze the material nearest the wall of the crucible shell 82 and thereby to form the skull 110 inside the crucible, similar to the skull 54 as described above in connection with FIGS. 1 to 11.

65 70 75 A stirring coil generally indicated by the reference nu-

meral 111 is provided for the crucible 82. As best seen in FIG. 17, the coil 111 comprises a series of turns which are clamped between bars 112 mounted on the outside of the crucible 82 by means of beams 113. The coil 111 is preferably constructed of tubing of electrically conductive material, such as copper, through which coolant is pumped to keep the tubing at a satisfactory operating temperature.

Current for the coil 111 and water for the coils 109 and 111 are transmitted from outside the enclosure 61 through a coupling assembly generally indicated at 114. Any suitable coupling arrangements for carrying electric currents and liquids through a wall subject to a pressure differential may be used. The flow diagram of the coolant and the circuit for the electric current in coil 111 are described below in connection with FIG. 25.

The tilting movements of the crucible assembly 82 are controlled in part by limit switches 115, 116 (see FIG. 20), which are operated by an arm 117 fixed on one of the trunnions 92. The wires from the limit switches 115 and 116 extend through a connector diagrammatically indicated at 118 (FIG. 17) and a cable 119 to the outside of the enclosure 61.

At the inner end of the rail 85 (the left hand end in FIG. 17), there is provided a stopping block 120 on which is provided a latch arm 121 which may be operated by a crank 122, and is provided at its end with a hook for engaging an axle 123 on the crucible assembly carriage. After the carriage with the crucible assembly is inserted in the enclosure 61 and the latch arm 121 is in place as shown in FIG. 17, the carriage is held in position and cannot move. Note that the wheels 84 at the side of the carriage under the beam 91 are provided with grooves which ride along corresponding ridges on their associated rails 85. At the opposite side of the carriage, the wheels 84a have cylindrical peripheries and ride along on flat rails 85a. The use of the cylindrical wheels 84a allows the expansion and contraction of the carriage which may be necessary because of the wide range of temperatures encountered within the enclosure 61, while the grooved wheels 84 and ridged rails 85 guide the assembly against lateral movement.

The crucible assembly 82 is filled with material to be melted by simply running the crucible outside the enclosure 61 and filling it by means of a crane or otherwise. Some of the material melted is supplied by the consumable electrode 67. The operating process generally follows that illustrated in FIGS. 5 to 11 above.

FIGS. 21 and 22

A crucible cover or shield 124 is provided, as shown in FIGS. 21 and 22. The shield 124 is supported on three radially extending arms 125 whose outer ends are attached to the lower end of vertical rods 126 which extend upwardly through suitable sealing members 127 into tubes 128 mounted on the upper side of the enclosure 61. A lead screw 129 extends downwardly through the center of each tube 128 and operatively engages the upper end of the rod 126. Each lead screw 129 is driven by a motor 130, mounted on the upper end of tube 128. The three motors 130 are operated concurrently so as to raise and lower the shield 124. The shield 124 is lowered whenever an arc is present inside the crucible 82, to conserve heat within the crucible.

FIGS. 23 and 24

These figures illustrate the details of construction of one of the non-consumable electrodes 78. Each electrode 78 comprises an upper coupling member 131, a lower coupling member 132, an outer power supply tube or cylinder 133, an inner power supply tube or cylinder 134, and an electrode tip 159. The coupling members are preferably made of copper as is the cylinder 134. The cylinder 133 is preferably stainless steel, and the parts are brazed together. The electrode tip 159 is preferably of graphite and is drilled to provide passages 159a and

159b for a flow of cooling inert gas, for example, argon or helium. The passage 159a communicates with a drilled passage 132a in the lower coupling member 132. The other end of passage 132a receives one end of a copper tube 135 which extends through the electrode and through the upper coupling member 131. Its upper end is connected to any suitable source of inert gas.

A nut 136 having a flange 136a is attached to the upper surface of the upper coupling member 131. The nut 136 is internally threaded and cooperates with a lead screw 137 extending through the center of the electrode to drive the electrode up and down. The lower end of the lead screw 137 is provided with a ball bearing 138 to minimize any friction there may be between it and the inside of the cylinder 134. A plurality of water inlet passages 131a are drilled into the upper coupling member 131. A similar plurality of water conduits 139 are located within the space between the cylinders 133 and 134 and convey cooling water from the inlets to the bottom of that space, the lower end of the water pipes 139 being spaced above the bottom coupling member 132. A similar plurality of water outlets 131b are drilled into the upper coupling member 131 and communicate with the space between the cylinders 133 and 134. The inlets and outlets are connected to any suitable water supply couplings. These couplings and the gas supply coupling hold the electrode against rotation when it is being driven up or down by the lead screw 137.

The parallel power supply tubes 133 and 134 carry the electrode current. The current may be supplied to the electrodes through any suitable connector mechanism (not shown).

FIG. 25

This figure shows diagrammatically the water circulation and electrical supply connections for the stirring coil 111 and for the cooling coil 109, which coils are shown in greater detail in FIG. 17. The stirring coil 111 is formed of copper tubing. While its primary function is to carry direct current, water is circulated through the tubing for the purpose of keeping it at a temperature where it will not lose its strength. A common water supply is used for both the stirring coil and the cooling coil 109. The cooling coil 109 is necessarily electrically connected to the crucible shell 86. In order to use a common water supply and at the same time transmit an electric current through the stirring coil 111, insulating sections must be used in some of the pipes.

The electric circuit for stirring coil 111 may be traced in FIG. 25 from one terminal of a power supply 140 through a wire 141, through a suitable connection to a water supply pipe 142, which extends by means of a suitable coupling through the wall of tank 61 and thence through a pipe 143 to coil 111, and out of the discharge pipe 144 to the outside of the tank 61 and thence through a suitable coupling to a wire 145 leading to the opposite terminal of the power supply.

The water supply for stirring coil 111 may be traced from a suitable inlet 146, an insulating pipe section 147, pipes 142 and 143, coil 111, pipe 144, and insulating pipe section 148 to a discharge outlet 149.

The cooling coil 109 is sectionalized for purposes of water circulation into six sections 109a, 109b, 109c, 109d, 109e and 109f. The sections 109a and 109b are connected in parallel and serve a zone at the upper part of the crucible shell 86. The coils 109c and 109d are likewise in parallel and serve a zone near the central portion of the shell 86. The coils 109e and 109f are in parallel and serve a zone at the bottom of the shell 86. The water supply for the three pairs of cooling coils may be traced in FIG. 25 from the inlet 146 through an insulating pipe section 147, through a T-connection into a pipe 150 which passes through the wall of the tank 61 at a suitable coupling, an insulating pipe section 151, and a manifold 152 which leads to all the cooling coils in parallel. The respective pairs of cooling coils discharge

through insulating pipe sections 153, 154 and 155 to discharge outlets 156, 157 and 158.

Power Supply for Electrodes FIG. 26

This figure illustrates diagrammatically the power supply connections for the crucible shell 86, the consumable electrode 67, and the three non-consumable electrodes 78, and for the motors which raise and lower the electrodes. Separate power supply equipment is used for each of the four electrodes. The power supplies are shown herein as generators but it will be readily understood that they may be other types of D.C. power supply equipment, for example, rectifiers supplied by alternating current. The generator 160 which supplies the consumable electrode 67 should have a substantially higher current rating than the other three. For example, it may have a 9000 ampere rating. The other three generators 161 which supply the non-consumable electrodes 78 have a lower current rating, for example, 3000 amperes. The current from the generators 160 and 161 passes to the electrodes 67 and 78 through suitable control apparatus, indicated diagrammatically at 162. Note that the control apparatus 162a for consumable electrode 67 is separate from the control apparatus 162b for the non-consumable electrodes 78. The circuit from the crucible shell 86 to the opposite terminals of the generators 160 and 161 is completed through a disconnect switch generally indicated at 163 and a bus bar 164. The disconnect switch 163 is shown in some detail in FIG. 15, and the bus bar 164 is shown in FIGS. 14 and 15.

The disconnect switch 163 comprises a plurality of parallel blades 165 which move between the switch fingers 168 attached to the bottom of the crucible shell, and a cooperating plurality of fingers 167 mounted on the top of the bus bar 164. The blades 165 are operated by a lever arm 163 through a linkage 169 connected to a crank arm 170 fixed on a shaft 171 which extends through a suitable coupling to the outside of the tank 61, where it carries another crank arm 172 operated by a fluid pressure cylinder 173. The switch blades 165 are kept in operating position between the fingers 168 and 167 except when it is desired to empty the crucible, at which time the switch blades 165 are pulled away from the fingers 168 and 167 by operation of the fluid cylinder motor 173.

The bus bar 164 is of a hollow square construction and is supplied with coolant, for example, water, through an inlet connection 174 outside the tank 61. The inlet connection 174 leads to a pipe 175 which extends nearly the full length of the bus bar 164 and opens at its inner end. The water flows from pipe 175 through the space between the pipe and bus bar 164 to an outlet connection 176 at the outer end of the bus bar. The bus bar is constructed of copper or other highly conductive material and must be cooled to withstand the high temperatures within the tank 61.

The control apparatus 166 for motor 75 which drives the consumable electrode 67 is separate from the control apparatus 166a for motors 80 which drive the non-consumable electrodes 78.

While we have shown and described certain preferred embodiments of our invention, other modifications thereof will readily occur to those skilled in the art, and we therefore intend our invention to be limited only by the appended claims.

We claim:

1. A furnace for making ingots of melttable material, comprising a crucible to receive material to be melted, means for connecting said crucible to one terminal of a source of direct electrical energy, a hollow electrode having a hollow tip adapted to cooperate with the material to be melted in the crucible, means for maintaining a subatmospheric pressure in the furnace, and means for supplying an inert gas to the furnace through said hollow electrode and tip.

2. A furnace for making ingots of melttable material, comprising a crucible to receive material to be melted, said crucible having a circular horizontal cross-section, means for connecting the crucible to one terminal of a source of electrical energy, an elongated consumable electrode of the material to be melted, means supporting the consumable electrode vertically above the center of the crucible, driving means operable to move the consumable electrode upwardly out of the crucible or to feed it downwardly into the crucible, means for connecting the consumable electrode to the other terminal of the source, three non-consumable electrodes radially spaced from the consumable electrode and equally circumferentially spaced from each other, and means operable when the consumable electrode is withdrawn from the crucible to connect said non-consumable electrodes to said other terminal of the source and to move the non-consumable electrodes downwardly to strike arcs between them and the material in the crucible, so as to raise the temperature of the material in the crucible without introducing additional material.

3. A furnace as defined in claim 2, in which said crucible comprises a shell of material having high heat conductivity, a solid skull of the material being melted adjacent the inside of the shell, and cooling means on the outside of the crucible and effective to keep said skull in a solid state.

4. A furnace as defined in claim 3, in which said cooling means comprises hollow tubing brazed on the outside of the crucible, and means for supplying a flow of coolant through the tubing.

5. A furnace as defined in claim 4, including an electrical coil having a vertical axis and encircling but insulated from said crucible, means for supplying direct current to said electrical coil to produce a unidirectional vertical field within said crucible, said coil being formed of hollow tubing, and electrically insulating conduit means connecting the interior of said hollow tubing to said coolant supply means, so that a flow of coolant fluid passes through the tubing.

6. A furnace for making ingots of melttable material, comprising an enclosure, a crucible within the enclosure to receive material to be melted, means for connecting the crucible to one terminal of a source of electrical energy, a hollow electrode, means for supporting the electrode with its lower end within arcing distance of the material in the crucible, means for connecting the electrode to the other terminal of the source to complete a circuit for supplying an arc between the electrode and the material, and means for circulating an inert gas through the enclosure including means to supply fresh gas to the enclosure through the hollow electrode, the gas flowing through the lower end of the electrode being effective to stabilize the arc at the lower end of the electrode, and means to withdraw gas from the enclosure through an outlet remote from the electrode.
